FEED LOCKING MECHANISM FOR SEWING MACHINES

Richard Kaier, deceased, late of Cranford, N. J.,
by Eleanor C. Kaier, executrix, Cranford, N. J.,
assignor to The Singer Manufacturing Company,
Elizabeth, N. J., a corporation of New Jersey

Application June 30, 1939, Serial No. 282,162

11 Claims. (Cl. 112—210)

This invention relates to sewing machines and more particularly to means for locking the feed-regulating mechanism thereof against adjustment, so that unauthorized persons may not 5 vary the length of the feed-stroke.

In the manufacture of clothing and other articles much of the work is paid for on the piece-work basis. Therefore, in order to increase production, operators will frequently lengthen 10 the feed-stroke of the feeding element, thereby producing stitches of greater length than desired by the manufacturer. In cases where the manufactured articles must conform to definite specifications as to stitch-length, this unauthorized 15 lengthening of the feed-stroke is serious inasmuch as it sometimes results in the rejection of an entire lot of the manufactured articles.

This invention therefore has as an object to provide a simple mechanism which will effectively 20 prevent the operator or other unauthorized persons from increasing the length of the feed-stroke.

A further object is to provide a feed-locking device of this nature which readily may be applied to sewing machines now in use, without the necessity of performing any machining operations thereon.

With the above and other objects in view, as will hereinafter appear, the invention comprises 30 the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 is a side view of a sewing machine embodying the present invention.

Fig. 2 is a vertical sectional view taken substantially on the line 2—2 of Fig. 1.

Fig. 3 is an enlarged longitudinal sectional view of the improved locking device, removed from the machine, together with its actuating key.

Fig. 4 is a perspective view of the improved 45 locking device.

Fig. 5 is a perspective view of the key which cooperates with the lock shown in Fig. 4.

Fig. 6 is a view showing a plurality of stop-screws adapted selectively to be used in the improved lock for varying the position of the feed-control lever, as hereinafter will be described.

Referring more specifically to the drawings, the invention is disclosed as embodied in a Singer Class 95 sewing machine comprising a cloth-plate 55 1, standard 2, overhanging arm 3 and a needle-

bar carrying head 4. A reciprocatory needle-bar 5, mounted in the head 4, carries a needle 6 which cooperates with a rotary loop-taker 7 to form stitches. The loop-taker is secured upon a shaft 8 journaled in bearings formed in bearing lugs 9 and 10 depending from the cloth-plate 1. The needle-bar is actuated from a main-shaft 11, journaled lengthwise in the arm 3, by a crank-and-link mechanism designated generally as x. The loop-taker shaft 8 is rotated from the main-shaft by means of a pair of bevel gears 12, 13, connecting the main-shaft with an upright shaft 14 journaled in the standard 2, and a second pair of bevel gears 15, 16, connecting the shaft 14 with the loop-taker shaft. 15

The machine also includes a work-feeding mechanism comprising a feed-bar 17, carrying a feed-dog 18, adapted to be given upward and downward and backward and forward movements thereby to give to the work the usual feeding movement after each retraction of the needle from the work. As is well understood, the length of the stitch formed is dependent upon the length of the feeding movement of the feed-dog. 20

The means for giving to the feed-bar, and the feed-dog carried thereby, their vertical and horizontal movements and the means for controlling the amplitude of the horizontal movement are similar to those disclosed in United States Patent to Miller and Diehl, No. 229,629, July 6, 1880. 25 30

Rising and falling movements are given to the feed-bar 17 by an eccentric 19 on the main-shaft 11 acting through a pitman 20 connected, at 21, to an arm 22 which projects laterally from the rear end of a rockshaft 23 journaled lengthwise 35 of the machine beneath the cloth-plate 1. At its forward end, the rock-shaft 23 carries a second arm 24 which is connected with the forward end of the feed-bar.

The means for giving to the feed-bar its end-wise reciprocating motions comprises an eccentric 25 secured upon the main-shaft 11, a block 26 surrounding the eccentric and a connecting rod 27 having its upper forked end 27a engaging the sides of the block 26 and its lower end pivotally 40 connected, at 28, to an arm 29 secured upon a feed-drive rock-shaft 30. At its forward end the rock-shaft 30 carries another arm 31 which is connected to the feed-bar 17 as shown in Fig. 2. Adjacent its upper end the connecting rod 27 has 45 pivotally connected to it, at 27b, one end of an anchor-link 32 the other end of which is pivoted, at 32a, to one arm of a normally stationary feed-regulating bell-crank lever 33 fulcrumed on a shoulder-screw 33a threaded into the arm 3. One 50 55

arm 33^c of the lever 33 carries an element which projects through a slot 3^a in the machine-frame for the purpose of adjustment. Horizontal movements of the block 26, under the influence of 5 the eccentric 25, causes the connecting rod 27 to be oscillated about its pivot 28. Due to the connection of the anchor-link 32 to the connecting rod 27 and to the normally fixed pivot 32^a, this oscillatory motion of the connecting rod causes 10 the pivot point 27^b to be moved in the arcuate path indicated by the dot-dash line y—y in Fig. 2. This movement in turn causes endwise movement of the connecting rod thereby effecting, through the arm 29, oscillatory motion of 15 the feed-drive rock-shaft 30, thus giving to the feed-bar its endwise reciprocations or work-feeding and return movements.

The amount of endwise movement given to the connecting rod 27, and consequently the amount 20 of horizontal reciprocation given to the feed-bar 17, is dependent upon the angular position of the anchor-link 32. This position may be changed by shifting the feed-regulating lever 33 about its fulcrum 33^a. The more nearly vertical is the 25 link 32 the less will be the endwise movement of the connecting rod 27 and the shorter will be the feed-stroke. Heretofore the lever 33 has been held in its various positions of adjustment by a clamp-screw which was under the control of the 30 operator, as shown in the above mentioned Miller and Diehl patent. Therefore, to increase the length of feed, operators have frequently released the clamp-screw and adjusted the feed-regulating lever 33 downwardly, in violation of orders to 35 the contrary.

The present invention provides locking means to prevent the operator from shifting the forward arm of the feed-regulating lever 33 downwardly to increase the stitch-length, whereby the stitch-length may be increased only by some person of authority having the necessary control key. This means comprises a clamp-screw 34, threaded into the arm 33^c of the feed-regulating lever, having a truncated conical head 35 provided with a concentric bore 36 and an eccentric aperture 37. The tapered head 35 is relatively smooth and is hardened to prevent rotation of the clamp-screw by means of pliers, wrenches or other readily available tools. Mounted upon the clamp-screw 50 34 is a sheet-metal stop-bracket 38 comprising a disk-like head 38^a having therein an aperture 38^b to receive the shank of the screw 34, a horizontally arranged portion 38^c, threaded to receive one of a plurality of adjustable stop-screws, later 55 to be referred to, and an upstanding leg 38^d having in its upper surface a notch 38^e the arcuate wall of which is adapted to contact with the shank of the clamp-screw 34. At its upper edge the disk-like portion 38^a is formed with an integral tab 38^f designed to be bent downwardly 60 over the conical head 35 of the screw 34, as shown most clearly in Fig. 3, thereby to prevent disassembling of the clamp-screw and the bracket 38. A threaded aperture 38^g in the portion 38^c 65 of the stop-bracket 38 is adapted to receive any one of a plurality of stop-screws designated as a, b, and c, in Fig. 6. The lower end of the stop-screw is adapted to engage the lower wall 3^b of the slot 3^a through which the clamp-screw 34 extends. Thus the wall 3^b, through the stop-screw and the leg 38^d of the stop-bracket 38, 70 limits the downward movement of the screw 34 and the feed-regulating lever arm 33^c. Inasmuch as each of the stop-screws is adjustable 75 lengthwise in the stop-bracket 38 each screw

affords a limited adjustment of the feed-regulating lever thereby providing a variation in the feed of approximately five stitches per inch. Major adjustments are effected by substituting a screw of different length.

After one of the screws a, b or c have been threaded into the bracket 38 and adjusted so that when its head rests on the wall 3^b the desired length of feed is secured, the screw 34 is turned to tightly clamp the parts in that position, the portion 38^a of the stop-bracket binding against the outer arcuate surface of the frame at opposite sides of the slot 3^a. This adjustment and clamping is effected by a foreman, or other authorized person, by means of a removable key 15 (Fig. 5) comprising a hub 40 having a circular extension 41 adapted to fit within the bore 36 in the head of the clamp-screw 34, a projecting eccentric pin 42 designed to fit within the eccentric aperture 37, and a transverse rod 43 adapted 20 to serve as a means for manually rotating the key.

It will readily be perceived that after the feed-regulating lever has been adjusted and locked by some authorized person and the key removed, it 25 is impossible for the operator to adjust the feed to lengthen the stitch.

Inasmuch as the above described locking device is a self-contained unitary structure it will be perceived that it may be readily substituted for 30 the conventional feed clamp-screw of machines now in use by merely unscrewing the clamp-screw (such as f² in the Miller and Diehl patent) from the feed-regulating lever and replacing it with the unit illustrated in Fig. 4.

Having thus set forth the nature of the invention what is claimed herein is:

1. A sewing machine combining a frame having a slot therein, work-feeding mechanism, a regulator for said feeding mechanism including 40 an adjusting lever aligned with said slot, means to lock said lever in its various positions of adjustment comprising a clamp-screw extending through the slot in said frame and threaded into said adjusting lever, and means carried by said clamp-screw and engaging an end wall of said slot to prevent movement of said screw toward said end wall.

2. A sewing machine combining a frame having a slot therein, work-feeding mechanism, a 50 regulator for said feeding mechanism including an adjusting lever aligned with said slot, means to lock said lever in its various positions of adjustment comprising a clamp-screw extending through the slot in said frame and threaded into 55 said adjusting lever, and adjustable stop means carried by the shank of said clamp-screw and adapted to engage an end wall of said slot to limit the movement of said clamp-screw toward said end wall.

3. A sewing machine combining a frame having a slot therein, work-feeding mechanism, a regulator for said feeding mechanism including 65 an adjusting lever aligned with said slot, means to lock said lever in its various positions of adjustment comprising a clamp-screw extending through the slot in said frame and threaded into said adjusting lever, a stop-bracket carried by the shank of said screw, and a stop-screw carried by said bracket and adapted to engage an 70 end wall of said slot to prevent movement of said screw toward said end wall.

4. A sewing machine combining a frame having a slot therein, work-feeding mechanism, a 75 regulator for said feeding mechanism including

an adjusting lever aligned with said slot, means to lock said lever in its various positions of adjustment comprising a clamp-screw extending through the slot in said frame and threaded into said adjusting lever, a sheet-metal stop-bracket carried by said clamp-screw and comprising up-standing end portions engaging the shank of said screw and a mid-portion connecting said end portions provided with a threaded aperture, 10 and a stop-screw threaded into said aperture and adapted to engage one end wall of said slot to prevent movement of said lever in a direction to lengthen the feed.

5. A unitary locking device for the feed-regulating lever of a sewing machine having a slot in the frame thereof in alignment with a portion of said lever, comprising a clamp-screw adapted to extend through said slot and to be threaded into said lever, said clamp-screw having a head 20 formed to receive a locking key, a stop-member carried by said clamp-screw and adapted to engage an end wall of said slot thereby to limit the feed-adjusting movement of said feed-regulating lever and a removable locking key fitted to said 25 head.

6. A unitary locking device for the feed-regulating lever of a sewing machine having a slot in the frame thereof in alignment with a portion of said lever comprising a clamp-screw adapted to 30 extend through said slot and to be threaded into said lever, said clamp-screw having a head of truncated conical form provided with a central bore and an eccentric aperture, a stop-member carried by said clamp-screw and adapted to engage one end wall of said slot thereby to limit 35 the feed-adjusting movement of said feed-regulating lever, and a key having portions complementary to said bore and aperture, adapted to rotate said clamp-screw to effect locking and unlocking of said feed-regulating lever.

7. A unitary locking device for the feed-regulating lever of a sewing machine having a slot in the frame thereof in alignment with a portion of said lever, comprising a clamp-screw adapted 40 to extend through said slot and to be threaded into said lever, said clamp-screw having a head formed to receive a locking key, a stop-bracket carried by the shank of said clamp-screw, a stop-screw threaded into said stop-bracket and 45 adapted to engage one end wall of the slot in said frame to prevent movement of said feed-regulating lever in a direction to lengthen the feed, and a key fitted to the head of said clamp-screw to rotate the latter to effect clamping and 50 unclamping of said lever.

8. In a sewing machine having a frame provided with a slot, work-feeding mechanism and a regulator for said feeding mechanism including an adjusting lever aligned with said slot, the combination with said adjusting lever of means to 55 lock said lever in its various positions of adjustment comprising a clamp-screw extending through the slot in said frame and threaded into

said adjusting lever, said clamp-screw having a head of truncated conical form adapted, upon rotation of said screw in one direction to frictionally engage said frame thereby impositively to resist shifting of said adjusting lever, means interposed between said clamp-screw and an end wall of said slot positively to prevent movement of said screw toward said wall, and a removable key adapted to engage the head of said clamp-screw to rotate the latter. 10

9. In a sewing machine, a locking means for the feed-adjusting lever thereof as set forth in claim 8, in which the head of the clamp-screw is formed with a concentric bore and an eccentric aperture, and in which the key has portions 15 adapted to fit within said bore and aperture to prevent relative rotation between the key and the clamp-screw.

10. A sewing machine combining a frame having a slot therein, work-feeding mechanism, a 20 regulator for said feeding mechanism including an adjusting lever aligned with said slot, means to lock said lever in its various positions of adjustment comprising a clamp-screw extending through the slot in said frame and threaded 25 into said adjusting lever, a sheet-metal stop-bracket carried by said clamp-screw and comprising offset end portions engaging the shank of said screw and a mid-portion, connecting said end portions, provided with a threaded aperture adapted to receive therein any one of a plurality of stop-screws of unequal lengths, the inserted stop-screw being adapted to engage one end wall of said slot thereby to position the clamp-screw and feed-adjusting lever to produce 30 different predetermined lengths of feed and to prevent movement of said lever in a direction to lengthen the predetermined feed-stroke. 35

11. A feed-regulating lever locking device adapted to be applied, as a unit, to a sewing machine having a frame formed with a slot therein and a feed-regulating lever located within said frame and having a portion aligned with said slot, comprising a clamp-screw having a shank portion extending through said slot and threaded into said feed-regulating lever and a head portion located exteriorly of said frame and formed to receive a locking key, said head portion being adapted, upon forward rotation of said clamp-screw, to apply pressure on said frame, adjacent said slot, the friction produced by said pressure tending to resist reverse manual rotation of said clamp-screw thereby to prevent ready removal of the clamp-screw, stop means carried by the shank of said clamp-screw and 40 engaging one end wall of said slot to prevent movement of said screw toward said end wall, and a removable key fitted to the head of said clamp-screw and adapted to facilitate manual rotation thereof. 45
